Primary Examiner — Kevin K. Rudzinski

(74) Attorney, Agent, or Firm — Pete Adams Law, PLLC

(57) **CLAIM**

The ornamental design for a bib, as shown and described.

DESCRIPTION

FIG. 1 is a perspective view of the bib;
FIG. 2 is a front view thereof, the rear view being a mirror image;
FIG. 3 is a left side view thereof, the right side being a mirror image;
FIG. 4 is a top view thereof, the bottom being a mirror image;
FIG. 5 is a front view of the bib folded, shown in its environmental use;
FIG. 6 is a rear view of the bib folded, shown in its environmental use;
FIG. 7 is a rear view of the bib folded, shown in an alternative environmental use; and,
FIG. 8 is a front view of the bib folded, shown in an alternative environmental use.
Broken lines in the drawings represent unclaimed environmental subject matter and form no part of the claimed design.

1 Claim, 6 Drawing Sheets
